UNITED STATES PATENT OFFICE.

AUGUST D. COOK, OF LAWRENCEBURG, INDIANA.

DESIGN FOR A WELL-STRAINER.

SPECIFICATION forming part of Design No. 26,799, dated March 23, 1897.

Application filed January 7, 1897. Serial No. 618,417. Term of patent 14 years.

To all whom it may concern:

Be it known that I, AUGUST D. COOK, a citizen of the United States, residing at Lawrenceburg, in the county of Dearborn, State 5 of Indiana, have invented and produced a new and original Design for Well-Strainers, of which the following is a specification, reference being had to the accompanying drawings, showing a part thereof.

10 Figure 1 is a perspective view of a well-strainer, showing my design. Fig. 2 is an exaggerated vertical sectional view of a portion of the same. Fig. 3 is a transverse section of the strainer through the slits or openings, these views being deemed necessary to 15 fully illustrate my design.

The leading feature of my design consists in a series of vertical rows of transversely-disposed slits or openings formed in the wall of 20 the strainer, which strainer, as is well known, is tubular. The slits or openings are formed at regular intervals and at right angles to the external surface of the strainer. The outer portions of these slits or openings, say for

about a quarter of their depth, have their 25 upper and lower surfaces parallel, but beyond said point the surfaces are abruptly diverged in vertical lines for a short distance and as abruptly again diverge in horizontal lines, so that at each side, or above and below those portions of the slits or openings formed by the parallel lines, right-angular recesses are produced.

A designates the wall of the strainer; B, the slit or opening; C C, the parallel surfaces 35 forming the outer portion of the same, and D D the right-angular recesses formed at the inner ends thereof.

What I claim is—

The design for well-strainers herein shown 40 and described.

In testimony whereof I affix my signature in presence of two witnesses.

AUGUST D. COOK.

Witnesses:

CHARLES L. SKINNER,
WILLIAM F. COOK.
